his Attorney.

UNITED STATES PATENT OFFICE.

RICHARD HARELL, OF DUNKIRK, NEW YORK, ASSIGNOR TO WILLIAM H. HARELL, OF SAME PLACE.

PORTABLE STEAM-BOILER.

SPECIFICATION forming part of Letters Patent No. 350,586, dated October 12, 1886.

Application filed July 1, 1886. Serial No. 206,830. (No model.)

To all whom it may concern:

Be it known that I, RICHARD HARELL, a citizen of the United States, residing at Dunkirk, in the county of Chautauqua and State of New York, have invented certain new and useful Improvements in Portable Steam-Boilers; and I do hereby declare the following to be a full, clear, and exact description of the invention, such as will enable others skilled in the art to which it appertains to make and use the same.

My invention relates to improvements in portable steam-boilers adapted to be used either for heating or power purposes; and it consists in certain novelty in the construction and arrangement of the various parts, all of which I will now proceed to point out and describe, reference being had to the accompanying drawings, in which—

20 Figure 1 is a vertical central section of a boiler embodying my invention. Fig. 2 is a horizontal section taken on line $x-x$ of Fig. 1.

Referring to the drawings, A represents a suitable base.

25 B is the jacket or outside casing, which is formed of two sheet-metal cylinders, one within the other, the space between the cylinders being filled with any suitable non conducting material.

30 C is the boiler; D, the outer shell of the same.

E is a water-leg, which surrounds the combustion-chamber F and rests on the base A.

35 f is a suitable grate forming the bottom of the combustion-chamber.

I is the feed-passage, closed by a suitable door, I'.

K is an opening for removing the clinker.

40 K' is a suitable casting for closing the opening K.

K² is an opening through which the clinker is passed into the ash-pit.

K³ is the ash-pit door.

45 a is the tube-sheet forming the top of the boiler.

b is the crown or tube-sheet over the combustion-chamber, and forming the bottom of the boiler.

c is a cast-iron ring resting on top of the boiler, and having an outwardly-projecting 50 annular flange, c', which rests on top of the jacket B, and closes the top of the space between the boiler-shell and said jacket.

d is a removable cover or plate, which rests on top of the ring c, and forms a smoke chamber, e on top of the boiler.

d' is a sheet-metal cover on top of the cover d, forming a space, d', above the cover d, which prevents radiation and waste of heat.

55 L are drop-tubes extending down into the combustion-chamber. Through the center of said drop-tubes are flues L', which extend up through the boiler and open into the chamber e, said flues or tubes being the direct flues of the boiler.

60 M are indirect or return flues, which extend from the chamber e down through the water-leg and open into the smoke-flue chamber D', formed between the shell D and jacket B. Said chamber D' communicates with the 70 smoke stack, D'.

65 Steam is conducted from the boiler by any of the well-known means. The products of combustion pass up through the direct flues L', through the drop tubes and boiler, into the 75 chamber e, then down through the indirect or return flues M into the smoke-flue chamber, and up again around the outside of the boiler-shell.

A boiler constructed as above described occupies but very little space, and at the same time has a very large heating-surface. It also combines the advantages of boilers provided with direct and return flues with those possessed by boilers provided with drop-tubes.

80 My improved boiler may be used for heating purposes, in which case I construct it of cast-iron; or it may be used for power purposes, and I then construct it of wrought-iron or steel plates.

85 Having thus fully described my invention, what I claim as new, and desire to secure by Letters Patent, is—

90 A boiler for generating steam, provided with a water-leg surrounding the combustion-chamber, drop-tubes extending down into the

combustion-chamber, and direct flues extending up through the drop-tubes and boiler, in combination with a chamber on top of the boiler, communicating with the direct flues, 5 and indirect flues communicating with said chamber and extending down through the water-leg, all arranged and operating substantially as shown and described.

In testimony whereof I affix my signature in presence of two witnesses.

RICHARD HARELL.
